DESIGN FOR A BATHING SHOE

Harry J. Haflin, New Haven, Conn., assignor to United States Rubber Products, Inc., New York,
N. Y., a corporation of Delaware

Application February 14, 1935, Serial No. 55,400

Term of patent 7 years

To all whom it may concern:

Be it known that I, Harry J. Haflin, a citizen of the United States of America, residing at 2127
Chapel Street, New Haven, county of New Haven,
State of Connecticut, have invented a new, original, and ornamental Design for a Bathing Shoe, of which the following is a specification, reference being had to the accompanying drawing, forming part thereof, in which:—

The figure is a perspective view of the bathing shoe showing my new design.

I claim:

The ornamental design for a bathing shoe, as shown.

Signed at the city of New York, county and State of New York, this 13th day of February, 1935.

HARRY J. HAFLIN.
